UNITED STATES PATENT OFFICE.

MILTON A. MCKEE, OF WESTERLY, RHODE ISLAND, ASSIGNOR TO C. B. COTTRELL & SONS COMPANY, OF NEW YORK, N. Y., A CORPORATION OF NEW JERSEY.

TREATMENT OF PRINTING-PLATES.

1,077,621.

Specification of Letters Patent.

Patented Nov. 4, 1913.

Application filed March 24, 1911. Serial No. 616,736.

To all whom it may concern:

Be it known that I, MILTON A. MCKEE, a citizen of the United States, and resident of Westerly, in the county of Washington 5 and State of Rhode Island, have invented a new and useful Treatment of Printing-Plates, of which the following is a specification.

In the preparation of printing plates 10 after the plate has been cast, its printing face and its back will be more or less distorted and the plate will be liable to be thicker at one portion than at another.

The object of this present invention is to 15 treat the plate so that its printing face and its back will be brought into substantial parallelism, thus obviating the necessity of using an underlay during the printing operation, the treatment of the plate also being carried out without the use of a matrix.

This invention is particularly directed to 20 the process of treating printing plates consisting in subjecting the back of the plate to local pressure along the same in close proximity to a shaving knife as the plate is being subjected to its shaving operation, the plate being placed face down upon the bed of the shaving machine without an interposed matrix, the said local pressure serving to assist 25 the shaving knife in crowding or forcing the metal away from the edge of the knife at the unsupported portions of the plate, *i. e.*, the parts not resting on the bed so that when the shaving operation is completed, the plate will be of substantially 30 the same thickness throughout.

Means for carrying out my process are represented in the accompanying drawings, in which,

40 Figure 1 represents a printing plate shaving machine suitable for carrying out my process. Fig. 2 is a top plan view of the machine. Fig. 3 is an enlarged detail longitudinal vertical section through the machine, Fig. 4 is an enlarged detail section taken in the plane of the line A—A of Fig. 5, Fig. 5 is an enlarged detail vertical longitudinal section at the shaving knife and spring-pressed fingers illustrating the action 45 of the knife and fingers with respect to the back of the printing plate. Fig. 6 is an enlarged transverse detail section of the inner spring-pressed plate holding roller. Fig. 7 is an enlarged detail view showing in side 50 elevation the device for adjusting the plate

cramping roller, Fig. 8 is an enlarged section taken in the plane of the line B—B of Fig. 7. Fig. 9 is a transverse section through a portion of a plate before it has been subjected to its shaving operation. Fig. 10 is a transverse sectional view showing the printing plate being subjected to the action of the shaving knife, Fig. 11 is a transverse section through a portion of the plate after it has been subjected to the shaving operation, Fig. 12 is a transverse sectional view showing the operation of subjecting the plate to heat and pressure, and Fig. 13 is a transverse section through a portion of the plate after it has been subjected to heat and pressure.

In all the views the scarcely visible greater or less prominence of the parts of the surface of the plates is somewhat exaggerated to render them distinguishable to the eye.

The main frame of the shaving machine is denoted by 1 and its reciprocating bed by 2. The bed rack is denoted by 3 and is driven backward and forward by a reversing pinion 4 mounted on a shaft 5 driven by a worm and gear connection 6, 7, from a drive shaft 8, which shaft in turn is driven from any suitable source of power, such, for instance, as a reversing motor 9, by a belt and pulley connection 10, 11, 12.

The movement of the bed may be reversed automatically and may also be reversed manually by the starting and reversing lever 13. The movement of the bed may also be controlled by the starting lever 13. The knife controlling lever is denoted by 14. These levers are suitably connected to the parts which they control and as they form no part of the present invention, their operation will not be specifically described herein.

The shaving knife is denoted by 15, and it is adjustably mounted on a member 16 which in turn is adjustably mounted upon the frame 17 adjustable in the main frame 1. The spring pressed plate engaging roller 18 is mounted in the vertically adjustable knife carrying member 16. The vertical adjustments of the shaving knife 15 are controlled by a hand wheel 19 having a geared connection 20, 21, 22, with the vertical adjusting screws 23, 24. A micrometer adjustment of the knife carrying member 16 may be provided by a hand shaft 25 provided with a worm and gear connection 26, 27, with the

shank of the handle 19*. This shaft 25 and its worm may be moved into and out of operative position by a hand lever 28.

The means which I have shown for exerting pressure upon the plate locally along the same, in close proximity to the knife, is constructed, arranged and operated as follows: A plurality of spring-pressed fingers are mounted upon a cross shaft 29 carried by brackets 30 forming a fixed part of the knife carrying member 16. Each of these fingers comprises a downwardly and inwardly extended arm 31 and an upwardly extended arm 32. The arm 31 is provided 10 with a barreled roller 33 arranged to roll along the back of the printing plate 34 in close proximity to the shaving knife 15. A screw bolt 35 extends forwardly from the uprising arm 32 of each spring-pressed finger, which bolt passes through a cross piece 36 of the brackets 30. A spring 37 is interposed between the cross piece 36 and an adjusting nut 38 on the said screw bolt. An adjusting nut 39 on the screw bolt 35, in 15 front of the cross piece 36, serves to limit the inward movement of the arm 32 of the spring-pressed finger and thereby the downward movement of the arm 31. The tension of the spring 37 may be adjusted by the nut 38. These nuts 38, 39, may be provided with lock nuts 40, 41, for locking the nuts 38, 39, in their adjusted position. A cramping roller 42 is carried by arms 43 supported upon a cross shaft 44 mounted eccentrically 20 in bushings 46 rotatably mounted in the brackets 30. Stops 45 on the brackets 30 limit the inward movement of the roller 42. This roller 42 serves to hold the printing plate firmly down upon the bed 2 of the machine as the plate is passed beneath the shaving knife 15.

Means are provided for adjusting the cramping roller 42 toward and away from the bed 2, which means consists in the present instance, of flanges 47 on the eccentric bushing 46, which flanges have elongated slots 48 through which clamping bolts 49 extend for securing the flanges rigidly to the brackets 30 at any desired position within the limits of their rotative movements.

In carrying out the process, the printing plate is laid face down on the bed 2 of the shaving machine. The back of the plate is then subjected to the action of the shaving knife 15. The plurality of independent spring-pressed fingers located adjacent to the knife will exert their pressure upon the back of the plate as it passes beneath the knife, thus serving to exert pressure locally 55 along the plate and assist the knife in crowding the unsupported parts of the plate, *i. e.*, the parts not resting on the bed, away from the edge of the knife, thus permitting the thicker portions of the plate to 60 be removed therefrom in one or more shav-

ings by the knife. The shaving operation is continued until a full shaving is made covering the entire area of the back of the plate, or until the plate has been shaved to the desired thickness. In either event, the plate will then be practically of the same 70 thickness throughout.

The printing plate has a certain amount of resiliency and hence when the various portions of the plate are deflected or pressed down during the shaving operation, such deflections are but temporary and as soon as the pressure is removed, such deflected portions will spring back to their normal position. Therefore it will be seen that when all of 75 the several shaving operations have been concluded, the printing face and the back of the plate will be substantially parallel, even though the plate itself is not absolutely 80 level.

If so desired, the plate, after the shaving operation, may be subjected to the action of heat and pressure for leveling the printing face of the plate as represented in Figs. 12 and 13.

In so far as certain features of my invention are concerned, it will be understood that I do not wish to be limited to all of the steps as disclosed herein, for some of such steps may be used without the others or in 90 connection with still other steps or modes of treatment, if so desired.

By the use of the expression "exerting pressure locally upon the back of the plate", I wish to be understood as contemplating 100 the independent application of pressure at different points upon the back of the plate.

What I claim is:

1. In the process of treating printing plates, to bring their printing faces and 105 backs into substantial parallelism, placing the plates on a flat surface, subjecting the back of the plate to the action of a shaving knife and to the independent application of pressure at different points along the same, 110 in close proximity to the shaving knife, for assisting the knife in forcing the unsupported parts of the plate away from its edge during the shaving action.

2. In the process of treating printing 115 plates, to bring their printing faces and backs into substantial parallelism, placing the plates on a flat surface, subjecting the back of the plate to the action of a shaving knife, and to the independent application of 120 pressure at different points along the same, in close proximity to the shaving knife, for assisting the knife in forcing the unsupported parts of the plate away from its edge during the shaving action, and finally subjecting the plate to heat and pressure for leveling the face of the plate.

3. In the process of treating printing plates, to bring their printing faces and 130 backs into substantial parallelism, placing

- the plates on a flat surface, subjecting the back of the plate to the action of a shaving knife and to the independent application of pressure at different points along the same, 5 in close proximity to the shaving knife, by a plurality of independent pressure devices, for assisting the knife in forcing the unsupported parts of the plate away from its edge during the shaving action.
- 10 4. In the process of treating printing plates, to bring their printing faces and backs into substantial parallelism, placing the plates on a flat surface, subjecting the back of the plate to the action of a shaving 15 knife and to the independent application of pressure at different points along the same,
- in close proximity to the shaving knife, by a plurality of independent pressure devices, for assisting the knife in forcing the unsupported parts of the plate away from its edge 20 during the shaving action, and finally subjecting the plate to heat and pressure for leveling the face of the plate.
- In testimony, that I claim the foregoing as my invention, I have signed my name, in 25 presence of two witnesses, this twenty-third day of March 1911.

MILTON A. McKEE.
